The ornamental design for a compartmented animal feeder, as shown and described.

DESCRIPTION

FIG. 1 is a top perspective view of a compartmented animal feeder showing my new design;

FIG. 2 is top plan view thereof;

FIG. 3 is a side elevational view thereof, the other sides being mirror images thereof;

FIG. 4 is a bottom plan view thereof;

FIG. 5 is a top perspective view of a second embodiment of FIG. 1;

FIG. 6 is a top plan view thereof;

FIG. 7 is an elevational view thereof, the other elevational views being substantially a mirror image thereof; and,

FIG. 8 is a bottom plan view thereof.
